CONVEYER DRIVE

Morris P. Neal, Quincy, Ill., assignor to A-B-C
Packaging Machine Company, Quincy, Ill.

Application October 30, 1941, Serial No. 417,119

6 Claims. (Cl. 198—135)

This invention relates to packaging machines, and particularly to means for governing the spacing between packages or cartons being handled on machines for sealing filled cartons, so as to effect savings in space not previously possible with such machines.

The sealing machines chosen to exemplify a preferred embodiment of the invention, comprise means for advancing cartons to the flaps of which adhesive has just been applied under the continuing action of a pressure member, which holds the flaps firmly together, until the adhesive has set, and the cartons thus have become firmly sealed.

In practical operation, adhesive is applied to the flaps of a filled carton, and this carton is then brought to enter the machine. A carton carrying and a pressure applying member are actuated by the entry of the carton, and move the carton forward sufficiently to provide space for the following carton. However, because of inertia, and of the character and limitations of the motion controlling means heretofore employed, the cartons heretofore have always moved forward somewhat more than has been necessary to provide space for the entry into the machine of the following carton. Thus, there has been in the sealing machines of prior art an empty waste space between the cartons, which has necessitated a longer, and thus a more expensive and cumbersome machine, than is necessary when this waste space is eliminated so that the cartons move through the machine end to end, fully utilizing the capacity of the machine.

A principal object of this invention is a machine for sealing filled cartons, in which the cartons travel through the machine end to end, substantially without any intermediate waste space.

Another object is a packaging machine, in which articles are conveyed more closely spaced than has heretofore been possible.

Another object is novel means for compensating for inertia effects in handling articles in conjunction with packaging operations.

Further objects will become apparent from the following detailed description.

I have illustrated a preferred embodiment of my invention in the accompanying drawings, in which—

Fig. 1 is a perspective view of a machine for sealing filled cartons in accordance with my invention;

Fig. 2 is a horizontal sectional view of a part of the regulating mechanism;

Fig. 3 is an elevational view taken on the line 3—3 of Fig. 1; and

Fig. 4 is a perspective view illustrating a type of carton which my improved apparatus is designed to seal.

Referring to Figs. 1 and 3 of the drawings, the reference numeral 1 indicates the frame of the machine shown here as consisting of a pair of channels 2 supported on legs 3 arranged at desired intervals along their length. Upon these channels 2 is mounted a series of rollers 4 serving as support for the cartons in their passage through the machine. The rollers are transversely mounted in the channels and closely spaced. Around them is placed an endless belt 6 preferably of heavy material and having an appreciable thickness. The belt is supported at one end upon the driving pulley 7 (Fig. 1) and at the opposite end upon an idler roller 8 (Fig. 3), and is driven from a suitable source of power, such as an electric motor 9 suitably mounted, for example, upon the lower portion of the frame and driving the pulley 7 by means of reducing gears 10 and a sprocket chain (not shown).

The upper portion of the frame resembles the lower portion in construction in that it likewise comprises channels 12, rollers 13 mounted in these channels and a belt 14, preferably of heavy material and having an appreciable thickness.

The rollers 13 are secured at their ends in the channels 12 by vertical pins 29 secured in the channels, and passing through holes in the ends of the roller shafts. Thus, the rotation of the rolls is unimpeded, and they are movable within the channels vertically, but not horizontally. Springs 15 are urging the rollers towards the lower ends of the channels. The channels 12 are rigidly connected with each other by means of cross bars 16. This entire upper channel assembly is supported by four racks 17, and is movable vertically on these racks, by means of a worm and worm wheel 18 and a crank 19. Thus, the distance between the upper channel assembly and the lower channel assembly can be readily adjusted to accommodate packages of different sizes.

For any given size carton the upper channel assembly is adjusted so that the cartons when introduced will raise the rollers 13 slightly against the pressure of their springs 15. The frame 1 is preferably provided at the receiving end with a roller table 20 and at its discharge end provision is made (not shown) for receiving and further dispatching or handling the sealed cartons.

Referring now to Fig. 2, the motor 9 receives its power from the leads 21 through two consecutive mercury tube switches, 22 and 23, so that the motor will run only when both of the switches are closed simultaneously, but will not run if either one of the switches is open. These switches are rigidly connected with trip bars 24 and 25, by means of plates 26. The paddles of the trip bars are positioned so that they will not in any manner obstruct the passage thereover of a carton, but when a carton is passing thereover will tilt the switches, so as to close the current.

If the motor is driven by multiphase current, then obviously more than one mercury tube switch will be required instead of each of the switches 22 and 23, in order to actuate the motor. In any event when a carton is passing over both of the trip bars, 24 and 25, the motor 9 will run, moving the carton forward by means of the conveyer belt 6, and when the carton leaves either one of the trip bars, the current will be broken, and the action of the motor 9 discontinued.

From the above description the function of the machine is apparent. A carton comes to the machine upon completion of a preceding filling operation, with the flaps folded but unsealed. It is placed on the receiving table 20; the overlapping faces of the unsealed flaps are coated with adhesive, and are pressed together. The carton is then pushed into the presser mechanism, over the trip bars 24 and 25. As the second of these bars (25) is tilted by the carton, the current is closed, the motor starts and the carton is carried forward into the machine, until the trailing edge of the carton leaves the first of the trip bars (24). The current is then broken, and the motor ceases to operate. Because of inertia, the belt, and carton carried thereby, will continue to move for a short distance and the distance between the trip bars 24 and 25 has been selected so that the carton will come to a stop at, or preferably immediately beyond the second trip bar (25). Thus, when the following carton is brought to enter the machine, the motor will not be started until this second carton is immediately adjacent to the preceding carton, with no intermediate space between them.

The distance the carton will be carried by inertia is generally characteristic of the machine, since the inertia of the motor and of other heavy moving parts so greatly exceeds that of the cartons, as to render practically negligible the influence of the weight of the cartons upon the distance they will be carried by inertia upon disconnection of the current to the motor. However, in unusual and extreme cases, particularly when very heavy and very light material, such as for example, lead shot and absorbent cotton, are being run on the same machine, I may prefer to provide an adjustment (not shown) so that the distance between the trip bars can be changed to compensate for the differences in inertia between the extremely heavy and the extremely light cartons.

In automatically actuated sealing machines of prior art there has been a waste space between the cartons of the machine, because of the inertia of the moving parts. This waste space between cartons is clearly illustrated for example, in Figure 1 of U. S. Patent 1,482,197 to Kimball, where the cartons in the machine are shown to be separated by a distance of approximately 30% of the length of the carton, and where, with the machine filled, the packages occupy only

67 1/2% of the sealing space, so that the machine is utilized only to the extent of 67 1/2% of its potential capacity.

In contradistinction, the machine of this invention, substantially eliminates the waste space between the cartons, by mechanically compensating for the inertia of the moving parts and the carton, as fully described above. In this manner more than 95% of the sealing space of the machine is utilized, with corresponding savings in dimensions, cost and efficacy.

While a specific embodiment has been described above, for purposes of illustration, the invention is clearly not limited to this particular form. The invention is applicable broadly to the intermittent conveying of objects, wherever close spacing is desirable. Instead of the trip bars and the mercury tube switches disclosed, I may use any means for closing electric circuits which can be actuated by the passage of an object. Thus, I may use not only pressure operable switch means, but also relays actuated by photoelectric cell means operating when the passage of the carton obstructs light beams spaced so that the distance between the beams substantially equals the distance the carton will travel by inertia after the current to the motor has been switched off. Further, if the cartons are conductors of electricity, or have coverings or inlays which are conductors, I may prefer to conduct the current through the cartons themselves, substituting contact brushes for the trip bars, and depending on the contact of a conducting part of the cartons with these brushes to open and close the circuit to the motor, directly or, when larger loads are necessary, by means of relays.

While I usually find it preferable to employ two separate switch means, spaced apart by a distance equal to that traveled by the carton by inertia, after the advancing power has been disconnected, I may accomplish the same result by having a single switch means, in conjunction with cartons of such uneven form (if a trip bar is employed); conductivity (if electrical conductivity of the carton is depended upon); or coloring pattern (if photoelectric actuating means are used), or otherwise irregular in character, that the single switch means is released and the current to the motor thus disconnected when only a part of the carton has passed the actuating position, and so that the trailing edge will be brought up to it by inertia.

The word "carton" I use in a broad sense, and understand it to include, as equivalents, any objects fed intermittently into a packaging machine, the close spacing of which is desired, and has not heretofore been fully attainable because of inertia.

It is thus apparent that the invention is capable of wide variations without departure from the spirit and scope thereof, so that it should be limited only by the following claims, in which it is intended to claim the subject matter of the invention as broadly as possible, in view of prior art.

I claim:

1. In a packaging machine, means for advancing the article in the machine, means for starting the action of said advancing means when the leading edge of an article has reached a certain predetermined station on the machine, and means for discontinuing the action of the advancing means when the trailing edge of the article has passed a point preceding that at which the leading edge actuated the starting means and

separated therefrom by a distance substantially equal to the distance which the article will move by inertia, after the power actuating the advancing means has been disconnected.

2. In a machine for sealing filled cartons, a presser member for applying pressure to the flaps of the carton, means for advancing the carton into the machine under the action of said presser member, a motor actuating said advancing means, means for starting the motor automatically when the leading end of a carton enters under the presser member, and other means for discontinuing the action of the motor when the trailing end of the carton has passed a point preceding that at which the leading edge actuated the means starting the motor, and separated therefrom by a distance substantially equal to the distance which the carton will travel by inertia, after the action of the motor has been discontinued.

3. In a machine for sealing filled cartons, means for applying pressure to the carton flaps, means for conveying the cartons through the machine, an electric motor actuating said conveying means, two switches in circuit with said motor so that the motor is operated when both of these switches are actuated by a carton, and is stopped when the carton ceases to actuate one of the switches, the distance between the said switches being substantially equal to the distance the carton will be carried by inertia, after the power to the motor has been disconnected.

4. In a machine for sealing filled cartons, means for applying pressure to the carton flaps, means for advancing the carton through the machine, and a motor actuating said advancing means, the starting of said motor being con-

trolled by a current-breaking device actuated by the leading edge of the carton and the stopping of said motor being controlled by a separate current breaking device actuated by the trailing edge of the carton, the said devices being spaced so that when the motion of the carton is arrested, the trailing edge will rest substantially at the point where the leading edge actuated the advancing means.

- 10 5. In a packaging machine, means for conveying the carton through the machine, an electric motor actuating said conveying means, and two separate automatic means so spaced as to connect the motor to its power supply during the introduction of a carton and to disconnect it when the carton and the advancing means have gained a momentum sufficient to carry the carton by inertia so far that the total travel of the carton is substantially equal to its length.
- 15 6. In a machine for sealing filled cartons, a presser member for applying pressure to the flaps of the carton, means for advancing the carton into the machine under the action of said presser member, a motor actuating said advancing means, means for starting the motor automatically when the leading end of a carton enters under the presser member, and separate means spaced so as to stop the motor automatically when the trailing end of the carton passes a point preceding that at which the leading edge started the motor, and separated therefrom by a distance substantially equal to the distance the carton will travel by inertia, after the motor has been stopped; said separate means comprising a pressure switch, the release of which will disconnect the power actuating the motor.
